(57) **CLAIM**

The ornamental design for an electric terminal, as shown and described.

DESCRIPTION

FIG. 1 is a rear view of an electric terminal according to the present invention.

FIG. 2 is a rear perspective view of the electric terminal of FIG. 1.

FIG. 3 is a left side view of the electric terminal of FIG. 1.

FIG. 4 is a top view of the electric terminal of FIG. 1.

FIG. 5 is a right side view of the electric terminal of FIG. 1.

FIG. 6 is a bottom view of the electric terminal of FIG. 1.

FIG. 7 is a front view of the electric terminal of FIG. 1.

FIG. 8 is a rear view of an electric terminal according to the present invention.

FIG. 9 is a rear perspective view of the electric terminal of FIG. 8.

FIG. 10 is a left side view of the electric terminal of FIG. 8.

FIG. 11 is a top view of the electric terminal of FIG. 8.

FIG. 12 is a right side view of the electric terminal of FIG. 8.

FIG. 13 is a bottom view of the electric terminal of FIG. 8.

FIG. 14 is a front view of the electric terminal of FIG. 8.

FIG. 15 is a rear view of an electric terminal according to the present invention.

FIG. 16 is a rear perspective view of the electric terminal of FIG. 15.

FIG. 17 is a left side view of the electric terminal of FIG. 15.

FIG. 18 is a top view of the electric terminal of FIG. 15.

FIG. 19 is a right side view of the electric terminal of FIG. 15.

FIG. 20 is a bottom view of the electric terminal of FIG. 15.

FIG. 21 is a front view of the electric terminal of FIG. 15.

FIG. 22 is a rear view of an electric terminal according to the present invention.

FIG. 23 is a rear perspective view of the electric terminal of FIG. 22.

FIG. 24 is a left side view of the electric terminal of FIG. 22.

FIG. 25 is a top view of the electric terminal of FIG. 22.

FIG. 26 is a right side view of the electric terminal of FIG. 22.

(Continued)

FIG. 27 is a bottom view of the electric terminal of FIG. 22;
and,

FIG. 28 is a front view of the electric terminal of FIG. 22.
The broken lines shown represent portions of the electric
terminal that form no part of the claimed design.
